UNITED STATES PATENT OFFICE.

EUGEN SCHÜRER, OF COLOGNE-MULHEIM, GERMANY, ASSIGNOR TO FELTEN AND
GUILLEAUME CARLWERK ACTIEN-GESELLSCHAFT, OF COLOGNE-MULHEIM, GER-
MANY.

METHOD OF EQUALIZING PAIRS OF SELF-INDUCTION COILS.

Application filed March 28, 1922. Serial No. 547,494.

To all whom it may concern:

Be it known that I, EUGEN SCHÜRER, a citizen of Germany, residing at Cologne-Mulheim, Prinz-Wilhelmstrasse 71, Germany, have invented new and useful Improvements in Methods of Equalizing Pairs of Self-Induction Coils, of which the following is a specification.

German Patent No. 329,481 describes a 10 pair of self-induction coils for loading four-wire telephone cables according to the Pupin system, in which, inside of a protecting-frame of laminated iron, two coils are arranged on both sides of a ring-shaped disc, 15 and are connected magnetically with this disc at the pole-places by means of iron fillets (connectors). The two coils, as side-coils, load, each for itself, one of the two side-circuits, and likewise the phantom-circuit 20 by action of the magnetic field, flowing in this case through both coils jointly. The winding of the coils therefore determines the amount of self-induction which the coil-pair supplies both for the side- and phantom 25 circuits.

It is well known that in order to prevent cross-talk between the three circuits, it is essential, besides other conditions, that lead- and return-lines of loaded circuits have 30 equal amounts of self-induction. The coil-pair, therefore, requires to be equalized in a manner that not only the halves of each side-coil, but also that the side-coils as halves of the coil-pair in phantom-connection 35 furnish respectively equal amounts of self-induction.

As far as the halves of the side-coils are concerned, this can be attained easily by equalizing adequately the windings. There 40 are difficulties arising, however, if at the same time the coils are to be equalized on equal amounts of their self-induction for the phantom-circuit. In this case equalization cannot be done by altering the windings, because otherwise either the equalization 45 of the halves of the side-coils, or (by altering both halves by the same number of windings) the side-inductivity of the coils would again be altered. Equalization could 50 be done only in a manner that the ends of the winding-halves of the coil to be equalized were wound jointly round such parts of the coil-pair that they cover only the duplex-field. For this purpose the fillets, connect-

ing the coils, would primarily come into 55 consideration. However, the performance of such an equalization on the composed coil-pairs is extremely laborious and wearisome.

The invention provides another means for this equalization, which, as is shown in the 60 following, is considerably simpler and more reliable.

As mentioned above, the coil-pair is placed inside an iron induction-protecting-frame, 65 which encloses the coils. The diagram represents the coil-pair with its frame in two different views. In these figures 1 and 2 represent the two side-coils of the pair, Z represents the disc, S and S represent the iron connecting-fillets, and R the external 70 protecting-frame. The protective effect of the frame consists in that it absorbs the outer leakage-fields effusing by the phantom-currents out of the fillet-points of the coils, 75 preventing hereby their further spreading outward.

Now, these leakage-fields contribute a small amount to the phantom-self-induction of each coil, i. e. to the halves of the total phantom-self-induction. It is evident that 80 by shifting the coil-pair within the frame in a manner that it approaches more or less the one or the other of the long sides of the frame, the leakage-fields flowing through the frame, and in consequence the small contributions to the halves of the phantom-self-induction, may be strengthened or weakened. For, in consequence of this shifting, the 85 aerial distances between the coil-poles and the frame, and consequently the magnetic resistances of the leakage-fields on each side of the pair, change in a reversed sense.

According to the invention, the equalization of the halves of the phantom-self-induction of the coil-pair is effected in such manner that the pair inside the frame is shifted towards one of the long sides so that the two amounts of the phantom-self-induction belonging to each coil, becomes equal. The 95 equality for instance in this case is ascertained by measurements (f. i. in a Wheatstone-bridge), as with the equalization of the halves of the side-coils.

What I claim is:

Apparatus for equalizing the self-induction in the pair of coils for loading four-wire telephone lines, comprising in combination a protective induction frame of mag- 105

netic material, an annular disc within said frame, two self-induction coils also arranged within said frame, one on each side of the disc, and iron connectors between the poles of the coils and the disc, said coils being adapted to be shifted towards one or the other of the longitudinal sides of the frame,

whereby the two amounts of duplex self-induction of the pairs of coils can be equalized.

The foregoing specification signed at Cologne, Germany, this 6th day of March, 1922.

EUGEN SCHÜRER.
